ELEVATING DEVICE FOR CAR DOORS

Carl Lute, Hammond, Ind., and Kenneth J. Tobin,
Chicago, Ill., assignors to Camel Company,
Chicago, Ill., a corporation of Illinois

Application June 1, 1931, Serial No. 541,144

5 Claims. (Cl. 16—99)

This invention relates to car doors and concerns itself primarily with an elevating device for such doors.

It is an object of this invention to provide an elevating device for car doors adapted to lift said doors from their normal frictional engagement upon a supporting surface and transfer the weight of said doors to rolling means for movement toward open and closed positions with a minimum of effort.

A further object is the provision of an elevating device for car doors embodying a two-part hanger assembly arranged for relative sliding movement to permit elevation of the doors, one of said parts serving as a fulcrum in such elevation.

Another object is the provision of hangers for car doors permitting ready removal of said doors from the car without disturbing the supporting track or track brackets.

It is an object, also, to provide a lifting device for car doors including hanger assemblies comprising parts adapted to have relative vertical movement and provided with means to limit such movement.

An object, as well, comprises the provision of a hanger assembly adapted for use in a door elevating device whereby parts of said assembly are retained against separation or loss during shipment.

A further object is the provision of a door elevating device employing hangers which insure substantially the same elevation of both sides of the door.

It is an object, moreover, to provide a door elevating device utilizing an operating lever and bracket means for mounting said lever upon the door, the bracket means being so constructed that the door may be elevated even though said lever be broken.

Other objects will become apparent as the description of the invention proceeds.

In the accompanying drawings
Figure 1 is a fragmentary elevation of a door with the lift device of the invention applied thereto.

Figure 2 is a horizontal section taken on line 2—2 of Figure 1.

Figure 3 is a vertical section taken on line 3—3 of Figure 1, the door being in lowered position.

Figure 4 is a view similar to Figure 3, the door being in elevated position.

Figure 5 is a vertical section taken on line 5—5 of Figure 1, parts being removed to more

clearly show the portion of the elevating device illustrated.

In the drawings, in which a preferred embodiment of the invention is illustrated, the numeral 10 designates a portion of a house car to which a track 11 is secured by means of a plurality of brackets 12, one of which is shown in part in Figures 3, 4 and 5 of the drawings. The track 11 is adapted to support the door 10^a when the latter is in its lowered or normal position. The engagement between the door and the track provides great frictional resistance toward the movement of the door.

Secured to the door adjacent the lower corners thereof is a plurality of hangers 13 and 14. Each of these hangers, as more clearly illustrated in Figures 2 to 4, inclusive, comprises a bracket 15 rigidly secured to the door by means of rivets 16 and a roller retaining member 17 slidably mounted for relative vertical movement with regard to the bracket 15. The roller retaining member 17 is maintained in proper position relative to the door and its corresponding bracket by means of the inturned flanges 18 and 19, formed on said bracket. A roller 20 is rotatably mounted in each of the members 17 by means of a pin or axle 21. The roller retaining member 17 is provided, additionally, with a pair of fingers 22 and 23, extending upwardly therefrom and toward the door for a purpose hereinafter set forth. The lower portion of said roller retaining member is provided adjacent the track 11 with an outwardly inclined flange 24. Secured to this flange is a plate member 25, extending upwardly and inwardly toward the car and overlapping a downwardly presented flange 26 formed on the track. It is observed that the roller 20 is mounted in the roller retaining member 17, preferably in engagement with the supporting track as clearly shown in Figure 1 of the drawings.

The adjacent sides of the brackets of the hangers 13 and 14 are provided with aligned openings 27, these openings being somewhat irregular in contour for a purpose which will appear hereinafter. Extending through these openings is an operating bar designated generally by the numeral 28. The operating bar comprises a length of pipe 29 and secured to the opposite ends of the pipe, as by rivets, is a plurality of castings 30 and 31. Each of these castings is provided with a lug 32 having a contour clearly indicated in Figures 3 and 4 of the drawings and positioned, when the door is in its normal or lowered position, in contact with the roller retaining member 17. The openings 27 formed

in the brackets of the hanger members 13 and 14 are substantially the same contour as the lugs 32 in order to permit their insertion through the brackets into operative engagement with the 5 roller retaining members.

Secured to the door intermediate the hangers 13 and 14, is a bracket member 33. This bracket member is provided with a boss 34 upon which is pivotally supported an operating lever 35. 10 Adjacent the boss is a flange 36. The bracket is provided with outwardly extending flanges 37 and 38, so shaped as to provide bearings 39 and 40 in which the operating bar 28 is journaled. It should be observed that the operating bar 15 is also journaled in the openings provided in the hangers. The bracket is provided, additionally, substantially centrally thereof, with a shoulder 41 and secured to the bar in alignment with said shoulder is a cam 42 with which the 20 operating lever 35 is adapted to co-act in order to produce rotation of the operating bar.

In the normal or lowered position of the door, as illustrated in Figure 1 of the drawings frictional engagement between the door and the 25 track is established in order to avoid undue movement of the door in either direction. When it is desired to move the door toward open or closed position a downward pull is exerted upon the operating lever 35. This downward movement of the lever is communicated to the operating bar 28 through the medium of the cam 42 mounted upon said operating bar and imposes a movement of rotation to said bar. During the rotation of the operating bar the lugs 32 will fulcrum upon the roller retaining members 17 and through the action of the operating rod upon the brackets of the hangers 13 and 30 14 the door will be elevated and its weight transferred from the track directly to the rollers 20. The elevation of the door is permitted because 40 of the relative vertically sliding relationship between the brackets of the hangers and the roller retaining members of said hangers. The elevation of the door is limited, however, by engagement 45 between the inturned fingers provided on the roller retaining members and the operating bar. In addition to this function, these fingers prevent disengagement of the roller retaining member from its corresponding bracket during 50 shipment and, moreover, these fingers insure elevation of both sides of the door to substantially the same extent. It is apparent if one side of the door should be elevated more quickly than the opposite side of the door, that engagement 55 between the fingers on one of the roller retaining members will limit the movement of the more quickly elevating side of the door and that elevation of the opposite side of the door will continue until its limit is reached.

60 By the construction of the bracket upon which the operating lever is mounted certain difficulties which may occur in actual practice are anticipated and provided for. Should the operating lever become broken or lost a separate lever 65 may be inserted under the boss and by this means a force applied to the cam secured to the operating bar in order to effect elevation of the door. In this mode of operation the flange 36, which effectively protects the boss, also acts as a stop 70 means for the separate lever. It is possible, moreover, because of the shoulder 41 formed on the bracket in alignment with the cam 42, to insert a separate lever under the shoulder and exert a downward force upon the cam in order to 75 elevate the door.

The two-piece construction of the roller retaining member to effect engagement with the track provides for ready and rapid removal of the door from the track for repairs or replacement. It is apparent that where the plate member 25 is incorporated as an integral part of the hanger construction it is impossible, particularly in the instance of the auxiliary door of a double door automobile application, to remove said door without removal of the track. By the 10 construction of this invention, however, it is only necessary to remove the rivets which secure the plate member to the hanger in order to permit removal of the door. The lower portion of the roller retaining member is inclined outwardly so 15 that the connecting rivets between said portion and the plate may more readily be driven and also more readily removed.

This invention is intended to comprehend within its purview all modifications and changes 20 which fall within the scope of the appended claims.

We claim:

1. In combination, a track, a sliding door adapted to have frictional engagement with said track, a pair of spaced hangers, each of said hangers including a bracket secured to said door and a member slidably vertically relative thereto, a roller rotatably secured to each of said members in engagement with said track, a rotatable operating bar journaled in said brackets, lugs provided on said bar in engagement with said members and means for rotating said bar whereby said lugs will fulcrum upon said members to elevate the door, said members being provided with means overlapping said bar and engageable therewith.

2. In combination, a track, a sliding door adapted to have frictional engagement with said track, a pair of spaced hangers, each of said hangers including a bracket secured to said door and a member slidably vertically relative thereto, a roller rotatably secured to each of said members in engagement with said track, a rotatable operating bar journaled in said brackets, lugs provided on said bar in engagement with said members and means for rotating said bar whereby said lugs will fulcrum upon said members to elevate the door, said members being provided with fingers overlapping said operating bar and engageable therewith to limit the elevation of said door.

3. In combination, a track, a sliding door adapted to have frictional engagement with said track, a pair of spaced hangers, each of said hangers including a bracket secured to said door and a member slidably vertically relative thereto, a roller rotatably secured to each of said members in engagement with said track, a rotatable operating bar journaled in said brackets, lugs provided on said bar in engagement with said members and means for rotating said bar whereby said lugs will fulcrum upon said members to elevate the door, each of said members being provided with a pair of spaced fingers overlapping said operating bar, said lugs lying between said fingers.

4. A door hanger comprising a roller supporting member, a roller rotatably carried by said member, a bracket member adapted to be secured to a door, said bracket member engaging and retaining said roller supporting member for vertical movement relative to the door, said roller supporting member being provided with a depending portion having a downwardly and out-

wardly inclined flange and a separate flange secured to said latter flange and lying in spaced relationship to said depending portion, for the purpose set forth.

5. In combination, a sliding door, a track positioned below said door comprising an angular member having a substantially vertically depending flange and a plurality of spaced hangers secured to the bottom of and supporting said door for sliding movement upon said track, each 10 of said hangers including a flange positioned

outwardly of said track flange having a vertical portion and an outwardly inclined portion lying below said track flange, a separate flange, means securing said separate flange to said outwardly inclined portion, said track flange being received between said separate flange and said vertical portion of said hanger flange, whereby said securing means and said flange may be removed to obtain removal of said door from said track.
